UNITED STATES PATENT OFFICE.

JOHN EDWARDS, OF SWANSEA, ENGLAND.

MEANS FOR AGITATING AND STIRRING MOLTEN METAL IN OPEN-HEARTH AND LIKE FURNACES.

Application filed May 7, 1926, Serial No. 107,393, and in Great Britain September 28, 1925.

This invention relates to an appliance for "paddling" the bath of molten metal in Siemens or other furnaces.

The appliance according to this invention comprises a paddle or a number of paddles carried by a rotatable arm, means being provided for moving the arm into or out of the furnace when desired, and means outside the furnace for rotating the arm.

10 In carrying this invention into practice the appliance consists of a hollow metal arm covered on the portion which enters the furnace with any suitable refractory material, paddles of refractory material being fixed

15 at or near to the end of the arm, the whole arm is rotated by suitable mechanism without the furnace, this would be carried on a truck running on the charging platform parallel with the furnaces or be supported

20 by an overhead travelling crane or gantry. The arm by means of the mechanism can be extended into or withdrawn from the furnace in a horizontal position, but when the arm has entered the door of the furnace the

25 end of the arm is lowered by the mechanism so that the paddles enter the bath at an angle and is rotated in this position, thereby agitating the metal with the object of assisting the impurities in coming to the

30 surface. Air may be admitted under pressure through the hollow metal core of the arm for cooling purposes and pass through suitable ducts formed in the core and refractory material to assist the oxidation of the impurities in the molten metal and reduce time taken for the charge.

In order that this invention may be clearly understood and readily carried into effect I have appended hereto a sheet of drawings 40 illustrating same, wherein

Fig. 1 is a side elevation showing the device in use.

Fig. 2 is a plan view.

Fig. 3 is a rear elevation.

45 Fig. 4 is a side elevation of the tilting mechanism.

Fig. 5 is a longitudinal view of the assembled paddles.

Fig. 6 is an end view of the paddler, and

50 Fig. 7 is a side view of the front end of the shaft for rotating the paddler.

Referring to the drawings the paddler comprises a suitable number and configuration of blades 1 carried by the front end of a hollow metal arm 2. The blades 1 are

held in position by a nozzle or head 3 which has a relatively narrow hollow shank 4 adapted to fit into a corresponding diameter bore in the front end of the arm 2. One or more transverse securing pins 5 is or are passed through the hub of the paddler 1 the front end of the arm 2 and the shank 4. The arm 2 is hollow and is fitted at its rear end over the front end of a shaft 6 to which it is locked by a dog clutch device 7 part of 60 which is carried by the arm 2 and the other part by the shaft 6. The nozzle 3, paddler 1 and the arm 2 are covered with a suitable refractory material.

The shaft 6 is rotated from an electric 70 motor or other power unit 8 which rotates a worm shaft 9, the worm 10 of which meshes with a worm wheel 11 on the shaft 6. Bearings 12 which support the shaft 6 for rotation are carried by brackets 13 which 75 are slidable along a pair of parallel guide rods 14 supported by a rectangular frame 15. Suitable abutments are provided to prevent the shaft 6 moving axially or endwise relatively to the bearings 12, so that if the 80 brackets 13 are moved backwards and forwards along the guide rods 14 the paddler 1 can be retracted or advanced as desired. A suitable method of effecting this movement of the brackets 13 is by means of one 85 or a pair of endless chains 16 each engaging an abutment on one of the brackets 13. Each chain is passed around a pair of sprocket wheels 17, one shaft 18 of one of the 90 sprocket wheels having a hand wheel or its equivalent 18^a whereby the said shaft 18 may be rotated and the chain or chains carry the bracket 13 backwards or forwards according to requirements. By this means whilst the shaft 6 is rotating the paddler 95 can be moved in or out of the bath 19. The shaft 6 is slidable through the worm wheel 11 and has a squared or other suitable sliding fit in the worm wheel for this purpose.

To enable the angle of the arm 2 to be raised as desired the frame 15 is suspended by suitable bearings and brackets from the worm shaft 10 so that it may be tilted. The tilting mechanism comprises a horizontal worm shaft 20 supported beneath the base of 100 the trolley chassis 21, the worm of the shaft 20 meshing with a worm wheel 22 fixed on a transverse shaft 23 to which is fixed an arm 24 having pivotally connected to its ends a pair of links 25 pivotally connected at their 105 110

upper ends to the frame 15. The worm shaft 20 has a hand wheel or its equivalent and this is preferably adjacent the hand wheel 18^a whereby one operator can adjust simultaneously if need be the tilting of the arm 2 and the advancing or retraction of the paddler.

The trolley carrying the appliance is preferably mounted upon wheels which may travel over rails, as shown in the drawings. The power unit of the device may be employed for propelling the trolley when desired.

Compressed air may be delivered through the hollow interior of the arm 2 and nozzle 3 into the bath of molten metal. The inlet into the arm 2 can be via a central passage 26 in the front end of the shaft, such passage having a lateral inlet 27 around which is disposed a bracket 28 which can be held stationary and a compressed air pipe attached thereto. The bracket 28 has an annular space surrounding the shaft 6 so that the rotation of the shaft does not interfere with the admission of compressed air into the passage 26.

What I claim is:—

1. A device for agitating molten metal in an open hearth furnace comprising a shaft, 30 agitating means carried by said shaft, means for rotating said shaft, means for tilting said shaft, and means for longitudinally advancing and retracting said shaft.
2. A device for agitating molten metal in an open hearth furnace comprising a trolley, 35 a frame tiltably mounted on said trolley, a shaft mounted in said frame for rotation and longitudinal movement with respect thereto, agitating means carried by said shaft, means 40 for rotating said shaft, means for longitudinally moving the same, and means for intro-

ducing compressed air through said shaft to the metal being agitated.

3. A device for agitating molten metal in an open hearth furnace comprising a shaft, 45 agitating means carried by said shaft, means for rotating said shaft, and means for tilting said shaft during rotation thereof.

4. In combination with an open hearth furnace, a track adjacent to said furnace, a 50 trolley movable along said track, a rotatable shaft mounted on said trolley for tilting and longitudinal movements, agitating means carried by said shaft for operation in a mass of molten metal in the hearth of said furnace, means for rotating said shaft, means to tilt said shaft, and means to move same longitudinally.

5. A device for agitating molten metal in an open hearth furnace comprising a trolley, 60 a frame tiltably mounted on said trolley, a shaft rotatably mounted in said frame, a rotatable shaft mounted on said trolley, link connections between said last mentioned shaft and said frame, and means for rotating said last mentioned shaft thereby to move said links to tilt said frame.

6. A device for agitating molten metal in an open hearth furnace comprising a trolley, 70 a frame tiltably mounted on said trolley, a pair of guide rods extending longitudinally of said frame, bearing members carried by and movable along said guide rods, an agitating shaft mounted in said bearing members, means for rotating said 75 shaft, and means for shifting said bearing members along said guide rods thereby to shift said agitating shaft longitudinally with respect to said frame.

In witness hereof I have signed this specification.

JOHN EDWARDS.
